(57) **CLAIM**

I claim the ornamental design for the scent diffuser, as shown and described.

DESCRIPTION

FIG. 1 is a perspective view of a scent diffuser, showing my new design.

FIG. 2 is a front view thereof.

FIG. 3 is a rear view thereof.

FIG. 4 is a left side view thereof, the right side view being a mirror image.

FIG. 5 is a top view thereof; and,

FIG. 6 is a bottom view thereof.

The broken lines represent unclaimed elements of the scent diffuser.
